UNITED STATES PATENT OFFICE

FRANK M. STEVENS, OF NEW YORK, N. Y., ASSIGNOR TO THE STEVENS
LOCOMOTIVE AND MACHINE COMPANY.

BALANCED SLIDE-VALVE.

SPECIFICATION forming part of Letters Patent No. 320,599, dated June 23, 1885.

Application filed July 10, 1884. (No model.)

To all whom it may concern:

Be it known that I, FRANK M. STEVENS, a citizen of the United States, and a resident of the city, county, and State of New York, have 5 invented certain Improvements in Balanced Slide-Valves, of which the following is a specification.

My invention relates to certain improvements in means for balancing or partly balancing a slide-valve, which means will be fully 10 hereinafter described.

In the drawings, which serve to illustrate my invention, Figure 1 is a vertical mid-section of the valve and its chest, the section of the 15 valve being taken on line 1 1 in Fig. 2. Fig. 2 is a side elevation, and Fig. 3 an end elevation, of the valve as a whole. Fig. 4 is a plan of the valve with the balance-plate removed. Fig. 5 is a cross-section of the valve, taken on 20 line 5 5 in Fig. 2. This view is designed to show the packing-strips and their supporting springs. Fig. 6 is a plan view of the under side of the balance-plate.

Let A represent the valve-seat, provided with 25 the usual ports, a a a; B, the steam-chest or valve-chest, provided with a cover, b, the lower face of which is parallel with the face of the valve-seat; and C, the valve-stem, arranged to play through a stuffing-box in the chest B, in 30 the usual way.

D is the body of the valve or valve proper. This is rectangular in form, open at the top, and provided with the usual lap-flanges, c, at 35 its base. In the upper edges of the end and side walls, d, are formed grooves e, which extend from side to side and from end to end of the body D. Into the grooves e in the side walls are placed side packing-strips, f, and in the grooves e in the end wheels are placed between strips f the end packing-strips, f'. These 40 latter cannot move endwise and become displaced, as they are embraced between the strips f, and to prevent the strips f from being displaced endwise I provide each with one or more 45 dowel-pins, g, which loosely engage holes at the bottoms of the grooves e, in which these strips are placed. The packing-strips f f' are supported on springs, and preferably on leaf springs, h h, placed in the grooves e in the end 50 walls, as indicated in Fig. 5, where one of these springs is clearly shown.

E is a balance-plate, which is provided with grooves e' e' in its lower face, which correspond exactly with the grooves e in the valve proper, and when this plate is in place, as 55 shown in Figs. 1, 2, 3, and 5, the upper edges of the packing-strips f and f' engage the grooves e', as clearly shown. The balance-plate E is made true on its upper face, and this face rests on and plays over the under face 60 of the cap b of the chest B.

Secured in the balance-plate E, or forming a part of the same, is a deflection-plate, F, which depends into the hollow of the valve proper, D, and has a concave lower face to 65 form a deflector to receive the impact of the exhaust-steam and deflect it downward toward the exhaust-port.

The steam from the chest has access under the packing-strips f f' at the open ends of the 70 grooves in which they rest, and holes i i, opening through the walls d into said grooves, may also be provided for the admission of steam. This exterior pressure of steam keeps the packing-strips pressed inward against the 75 inner walls of the grooves in which they rest, thereby insuring a steam-tight joint, and it also keeps the balance-plate E pressed up to its seat on the chest-cover b. The surface upon which the steam-pressure is exerted to 80 press the plate E upward is equal to the entire under surfaces of the packing-strips and the under surface of that portion of the plate E that is exterior to said packing-strips. To equalize or counterbalance a portion of this, 85 I cut away or rabbet a portion of the upper bearing-surface of plate E at j, so that steam may have access to a part of said upper surface. The amount of surface thus exposed to the pressure of the steam may be regulated 90 and proportioned at will by the maker. I prefer to rabbet the upper exterior edge of the walls d of the valves, as at k, in order to insure free access of the steam to the under side of the margin of cap E. This is the more necessary 95 where the chest-cover b is so low as to press the cap E down very nearly to the wall d of the valve proper.

The valve-stem may be attached to the valve by means of a T-head on the stem engaging a 100 keeper, l, on the valve, or in any good way. The function of the springs h is mainly to

keep the cap E pressed up to its seat where there is no steam-pressure on the valve; but they also insure the steam getting under instead of over the packing-strips.

5 As the top of the valve proper, D, is open, there is no tendency for the valve to lift from the pressure upward of the exhaust. This pressure is received by the deflector F.

In order to strengthen the valve, which in some cases is quite long, I usually provide it with ties or bridges *m m*, one or more, which extend across it from side to side, and are cast in one piece with it, as shown in Fig. 4. The deflector F has cross-slots *n n* to receive these ties.

5 Having thus described my invention, I claim—

1. A balanced slide-valve comprising a valve proper with grooves in its top to receive packing-strips, the said packing-strips, and a balance-plate having grooves in its lower face to receive the upper edges of said packing-strips and mounted on the latter, all constructed and arranged to operate substantially as described and shown.

2. A balanced slide-valve comprising the open-topped valve proper of rectangular form, provided with grooves *e* in the tops of its sides, the packing-strips *f f'*, the springs *h* that uphold said strips, and the balance-plate E, provided with grooves *e'* in its lower face, the said packing-strips being fitted into said grooves *e* and *e'*, substantially as and for the purposes set forth.

3. A balanced slide-valve comprising the valve proper, D, provided with grooves for the packing, the said packing, and the balance-plate E, provided with grooves to receive the packing, and with the pendent deflector F, substantially as shown, and for the purposes 40 set forth.

4. The combination, to form a balanced slide-valve, of the valve proper, D, provided with grooves to receive the packing, the said packing, and the balance-plate E, also provided 45 with grooves to receive the packing, and with rabbets *j* at its upper edges, to provide a surface for the steam-pressure to act on, substantially as and for the purposes set forth.

5. The combination, to form a balanced slide-valve, of the open-topped valve proper, D, provided with straight grooves *e* to receive the springs *h* and packing-strips *f f'*, and with the exterior rabbets, *k*, the said springs and packing-strips, the balance-plate E, provided with 55 grooves *e'*, to receive the upper edges of the packing-strips, and with rabbets *j*, and the pendent concave deflector F, secured to or forming a part of plate E, all constructed and arranged to operate substantially as set forth. 60

In witness whereof I have hereunto signed my name in the presence of two subscribing witnesses.

FRANK M. STEVENS.
